UNITED STATES PATENT OFFICE.

HERBERT E. METCALF, OF SAN LEANDRO, CALIFORNIA, ASSIGNOR TO THE MAGNAVOX COMPANY, OF SAN FRANCISCO, CALIFORNIA, A CORPORATION OF ARIZONA.

TUBE GRID AND METHOD OF MAKING SAME.

Application filed May 18, 1925. Serial No. 30,947.

This invention relates to an improved grid for radio vacuum tubes and to a method of manufacturing such grid. The primary object of the invention is to provide such an 5 improved grid and to manufacture the same by a simpler and cheaper method than has been used heretofore.

In the ordinary radio vacuum tube the grid comprises a plurality of wires strung horizontally between two spaced vertical posts or 10 a wire spiral hanging in a vertical position within the tube. The filament is positioned in the opening extending longitudinally and vertically through the grid. A grid of the 15 first type just mentioned is ordinarily formed on the posts when assembling the two parts together. My invention contemplates the manufacture of a grid as an independent article, whereby the same can thereafter be 20 assembled bodily in the tube.

More specifically my improved method comprises the weaving of the grid-forming wires into a sheet of a pattern which can thereafter be cut up into pieces and readily 25 formed into grids of the desired configuration. A further object of my invention is the provision of such an improved method and the improved grid made thereby.

In the accompanying drawing I have illustrated one specific embodiment of my invention, but it will be understood that the invention can be otherwise embodied and that the drawing is not to be construed as defining or limiting the scope of the invention, the 35 claims appended to this specification being relied upon for that purpose.

Referring to the figures of the drawing,

Fig. 1 is a face view of a portion of a woven wire screen or sheet of a pattern adapting the same to be used in manufacturing my improved grids.

Fig. 2 illustrates a portion cut from the sheet and from which a grid is formed.

Fig. 3 is a perspective view illustrating a 45 grid formed from the wire piece shown in Fig. 2.

In the drawing, 1 indicates a plurality of uniformly spaced wires which are tied together and formed into a sheet by spaced groups 2 of wires extending in a relatively right angular direction thereto. This wire sheet is thereafter severed in relatively right angular directions to form the same into independent grid-forming pieces like that shown in Fig. 2. To form these pieces the sheet of Fig. 1 is cut longitudinally through the center of the alternate wire groups 2, as for example on the line *a—a*. These resulting strips are then severed into lengths equal to the length of the grid it is desired to make. 50 These pieces are then formed into a grid of the shape shown in Fig. 3, the two ends of the strip being secured together in any manner desired.

The completed grid shown in Fig. 3 is the 55 piece shown in Fig. 2, bent about the central portion *b* and having the ends *c* thereof secured together. The wires 1 form the sides of the grid and the edges *d* are formed from the groups 2 of wires heretofore described. 60

Having thus described my invention, what I claim as new and desire to secure by Letters Patent is:

1. A method of manufacturing grids consisting of weaving wires in relatively transverse directions in a manner forming a sheet having spaced wires running in one direction and tying them together by relatively spaced groups of wires woven therethrough in a relatively transverse direction, and forming a portion of such sheet into an oblong tubular grid having the sides thereof formed of the said spaced wires and the ends of the sides formed of the said groups of wires. 75

2. A grid for vacuum tubes, comprising 80 an elongated tubular member formed of parallel wires extending at right angles to the longitudinal axis of the grid, and stiffening wires folded into the first-mentioned wires at the narrower sides of the grid and extending 85 parallel to the longitudinal axis of the grid. 90
